F. M. ALTFATHER

TRAIN HOSE NIPPLE ASSEMBLING TOOL

Filed Feb. 6, 1925

FIG. 1.

FIG. 2.

FIG. 3.

Frederick M. Altfather
INVENTOR

BY Frank H. Schwartz
ATTORNEY

UNITED STATES PATENT OFFICE.

FREDERICK M. ALTFATHER, OF COVINGTON, VIRGINIA, ASSIGNOR TO COVINGTON MACHINE COMPANY, INC., OF COVINGTON, VIRGINIA, A CORPORATION OF VIRGINIA.

TRAIN-HOSE NIPPLE-ASSEMBLING TOOL.

Application filed February 6, 1925. Serial No. 7,323.

This invention relates to tools for operating on nipples of train hose, and comprises all improvements disclosed in this application. The primary object is to produce an 5 easily made tool which is reliable in operation.

The above and other objects which will hereinafter appear, are attained by new and useful improvements as disclosed in this application. To enable others skilled in the art to fully understand the essential features of the improvements, drawings have been annexed as a part of this disclosure.

Fig. 1 is a longitudinal section through the barrel on line A—A and through the stock on line B—B, of Fig. 3.

Fig. 2 is a top plan view of the tool.

Fig. 3 is a right end elevation of the tool.

The tool comprises a stock 1 horizontally pivoted at 2 to a carrier or slide 3 for operative movement similar to the construction shown for the nipple puller and nipple assembler in Figs. 9 and 12 of Patent 1,461,578.

Stock 1 is provided with a hole 4 in which is secured by pin 5, the reduced cylindrical end 6 of the preferably square barrel 7.

Barrel 7 is primarily square to permit of its being easily and accurately held while being slotted. Four longitudinal slots 8 are provided in the faces of the barrel. Each two opposite slots 8 are connected by an end slot 9. A spring wire 10 extends across each end slot 9 and into the opposite longitudinal slots 8, thence emerging to provide two curved portions, which again reenter slots 8 and extend along the slots 8 within stock 1.

To prevent the wires from coming out of slots 9, the end portions of the barrel are bent to at least partly close the slots 9. A spring 11 normally pushes a floater or plug 12 against the ends of the wires and barrel.

While wires 10 will ordinarily spring outwardly against the inner surface of nipples placed thereon to center the nipples, these wires do not always have sufficient resilience to be always satisfactory in service, especially in the smaller size used for signal hose nipples. But by providing a relatively powerful auxiliary spring 11 which forces floater 12 against the ends of the spring wires 10, the latter are forced outwardly with sufficient force.

In operation, a nipple is slipped over the 55 end of the barrel 7 forcing wires 10 inwardly

and forcing the ends of the wires to the left against floater 12 which may move back against spring 11 if wires 10 are forced in sufficiently far. Thus by the aid of spring 11 the wires 10 press firmly outward against the inside of the nipple to center it. The left end of the nipple abuts against face 13 of stock 1. As the carrier 3 moves to the right, the neck of the nipple is forced into the hose. By making tools of suitable sizes, the nipples of air, steam and signal hose can be assembled with the hose.

It is to be noted that the longitudinal center line of barrel 7 is substantially lower than the center line of pivot 2. This insures against the barrel being pushed upward as the neck of the nipple is forced into the hose.

To insure the barrel properly entering the hose nipple, an adjusting means is provided between the stock and carrier. Thus the stock has a recess 14, between the lower wall portion 15 of which and the carrier 3, a wedge 16 engages. The upper portion 17 and the rear parts 18 of stock 1 are cut away to provide clearance. Wedge 16 tapers upwardly to correspond with wall 15, and has a shank portion 19 engaging between pin 20 and head 21 of adjusting screw 22. By adjusting screw 22 upward wedge 16 is forced against wall 15 thereby tilting the outer end of barrel 7 upwardly. By lowering the screw the barrel 7 is permitted to move downward. While this wedge adjustment is shown on an assembling tool, it is intended for use on both pulling and assembling tool, for example on such tools as shown in Patent 1,461,578.

All changes which properly come within the spirit and range of equivalency of the following claims are intended to be embraced within the scope of the claims.

I claim:

1. In a device for operating on train hose nipples, a carrier, a stock pivoted to the carrier, and an adjustable wedge engaging between the carrier and stock at a location below the center of the pivot of the stock to the carrier, the wedge tapering in an upward direction.

2. The device set forth in claim 1 with adjustable means on top of the stock adapted to pull the wedge upwardly.

3. A nipple assembling tool comprising, a barrel having longitudinal slots therein, and spring wires normally having portions

thereof in said slots and other portions outside of said slots, said other portions adapted to be pressed into said slots.

4. The nipple assembling tool set forth in claim 3 in which the barrel is polygonal.

5. The nipple assembling tool set forth in claim 3 in which the barrel is polygonal, and with the slots located in opposite faces of the polygonal barrel.

10. 6. A nipple assembling tool comprising, a barrel having slots extending longitudinally on opposite sides thereof, and a slot across the end of the barrel connecting each two slots on opposite sides of the barrel, and a 15 continuous spring wire engaging in all three said slots.

7. The nipple assembling tool set forth in claim 6 with the slotted end of the barrel bent to at least partly close said end slot 20 to retain the spring wire herein.

8. A nipple assembling tool comprising, a stock, a barrel secured to the stock and extending outwardly therefrom, and having longitudinal slots in opposite sides of the 25 barrel extending to the extreme end of the

barrel which is secured to the stock, wire secured to the barrel and having portions engaging in the slots and adapted to slide beyond the said extreme end of the barrel, and a spring in the stock normally tending 20 to push the ends of said wire portions when said portions project beyond said extreme end of said barrel.

9. The nipple assembling tool set forth in claim 8 in which the wire is spring wire. 35

10. The nipple assembling tool set forth in claim 8 in which a member is interposed between the spring and the ends of said wire portions.

11. A carrier, a stock substantially horizontally pivoted to the carrier, adjusting means engaging between the stock and carrier at a location substantially lower than the center line of the pivot, a hose nipple assembling member secured at one end to the stock 40 and extending outward from the stock, the longitudinal center line of the assembling member being substantially lower than the center line of the pivot. 45
